MEANS FOR STARTING FREE PISTON ENGINES

Hermann Jänicke, Dessau, Germany, assignor to Hugo Junkers, Bayrisch-Zell, Oberbayern, Germany, Therese Junkers, née Bennhold, Gauting, Germany, administratrix of said Hugo Junkers, deceased

Application May 17, 1934, Serial No. 726,167
In Germany May 23, 1933

6 Claims. (Cl. 230—56)

My invention relates to means for starting free piston engines. It is an object of my invention to provide improved means for starting such engines.

It has already been suggested to start free piston engines by means of springs placed under tension, the energy thus stored in the springs being made to act on the freely movable masses. In free piston engines comprising a gas compressor forming the energy consuming unit, it has been suggested to fill the compressor spaces with compressed gas, while the freely moving masses are locked in their position by suitable means, and to thereafter release the locking means, thus allowing the freely moving masses to be accelerated by the expanding gas and to compress the gas in the motor cylinders.

When proceeding according to these prior suggestions, only a single impulse can be imparted to the freely moving mass and it is therefore necessary to create already during the first two strokes occurring in opposite directions in the motor as well as in the energy consumer the conditions of operation corresponding to normal operation, which include sufficient compression of the motor charge and production of a final pressure in the compressor sufficient for ordinary operation, in order to provide for a faultless operation of the machine. To create these conditions in a reliable manner is connected with great difficulties, more especially in the case of multistage compressors.

According to the present invention this drawback is obviated by providing a separate energy storer connected with the freely moving masses and charged with the energy required for the starting of the engine, which is effected in the following manner: The energy stored in the energy storer is transmitted to the freely moving mass which now executes its first stroke, whereby the motor charge is compressed. The compressed charge in the motor cylinder is now ignited and the gases of combustion force the freely moving mass back, whereby the energy storer is partly reloaded. This new quantity of energy available is now transmitted to the freely moving mass during the next following starting stroke. On the charge in the motor cylinder being now ignited, the freely moving mass is once more imparted an impulse and the energy storer is again reloaded up to part of its first charge, and so forth. Thus during several starting strokes, the energy storer delivers to the freely moving mass gradually decreasing quantities of energy, while this mass, during the intermediate strokes,

to the storer, until finally these latter quantities of energy have become equal to zero, so that the storer runs idle. At the same time the energy consumer, for instance a compressor, is controlled in such manner, that when beginning the starting, it will take up little or no energy, the energy taken up increasing however from one working stroke to the other in the same proportion as the delivery of energy from the energy storer decreases, so that when this latter begins to run idle, 10 the part of the engine, which consumes energy, has reached its full output. The gradual loading of the energy consumer may be effected automatically in dependency from the unloading of the starting energy storer or the gradual unloading of 15 the starting storer may be effected automatically in dependency from the increasing loading of the energy consumer. Preferably the starting energy storer is so designed that it can be disengaged from the freely moving mass after normal conditions of operation have been reached.

Preferably when charging such storers before the starting, the freely moving masses are locked in their position in a well known manner, by suitable locking devices, which are released, when the 25 starting stroke begins.

If gas under pressure is used for starting, the gas may be caused to flow into the storing cylinder from a reservoir during the starting stroke. I may however also supply starting energy to the 30 storer under the form of chemically bound energy, for instance in an explosive, and in that case no locking means are required for locking the freely moving masses. If compressors are used, throttling means, which are gradually opened during 35 the starting process, may be inserted in the supply pipe and in the case of multistage compressors also between the individual stages.

The amount of starting energy required and consequently also the size of the starting storer may be reduced by reducing the resistance to be overcome during the starting stroke, for instance by diminishing the quantity of gas to be compressed in the motor cylinder, part of the charge in the motor cylinder being re-exhausted for this 40 purpose. Preferably this re-exhausting is rendered dependent from the gradual translation of the flow of energy from the starting storer to the energy consumer. Similarly the fuel feed to the motor may be influenced in dependency from this 45 translation, a smaller quantity of fuel than required during normal operation being for instance fed during the start, to be thereafter gradually increased in the course of energy translation.

In the drawings affixed to this specification and 50 55

forming part thereof some embodiments of an engine provided with a starting device according to my invention are illustrated diagrammatically by way of example.

5 In the drawings—

Figs. 1 and 2 are axial sections of two embodiments of a free piston engine according to my invention, a pneumatic energy storing device.

10 In Figs. 1 and 2, corresponding parts are marked with the same reference numerals.

15 Referring first to Fig. 1, the free piston engine contains two reciprocating bodies, each comprising a motor piston 1, a compressor piston 2 and a storing piston 3, reciprocating in opposite directions in a motor cylinder 11, compressor cylinders 12 and storing cylinders 13, respectively. 4 and 5 are inlet ports and exhaust ports provided in the wall of the motor cylinder 11. The compressor cylinders 12 are provided with suction valves 7 and pressure valves 8. In order to secure exact opposite reciprocation, the reciprocating bodies are coupled with each other by means of a coupling device comprising toothed racks 14, 14', connected to the compressor pistons 2, respectively, and a pinion 15 engaging the toothed racks and rotatably secured to the casing (not shown) of the engine. 16 is an inlet nozzle for delivering fuel into the cylinder 11. The reciprocating bodies can be arrested by means of a locking device comprising a latch 18 releasable by means of a spring-loaded hand lever 19 and cooperating with a locking tooth 17 provided on the rack 14. In the position of the locking device shown in Fig. 1 the reciprocating bodies are locked approximately in their outer dead centre positions.

20 Each storing chamber 9 is connected to a supply of compressed air (not shown) by means of a pipe 21, a starting valve 22 and an inlet pipe 23. In the engine shown in Fig. 1 a starting storer is provided on each side of the engine. If desired, however, a storing device may be provided only on one side, influencing the other side of the engine by means of the coupling gear 14, 14', 15.

25 In order to obtain a suitable operating diagram of the storing device and to reduce its dimensions, means are provided for allowing compressed air to flow into the storing cylinders during a portion of the starting stroke. In order to maintain the delivery of compressed air to the storing cylinders and to stop it a predetermined time after the beginning of the starting stroke, an outlet 25 is provided in the wall of each storing chamber 9 in such manner, that the storing pistons 3 move past the outlets 25 only after having carried out a considerable portion of their starting stroke. The outlets 25 constitute connections between each storing chamber 9 and auxiliary cylinders 26', in which auxiliary pistons 26 are arranged for reciprocation, the piston rods 27 of which extend into the pipes 23 and which comprise bores 28, through which compressed air flows to the storing chambers 9, until the pistons 26 are forced apart by the air escaping from the storing cylinders 9 through the openings 25. 27' are buttons for re-setting the pistons 26 into their initial positions after the stopping of the engine.

30 In order to unload the energy consumer, comprising compressor pistons 2 and compressor chambers 6 forming part of cylinders 12, during the outward stroke following the starting stroke and to re-charge the storing devices by compressing the air contained in the storing chambers 9, a pressure regulating valve 32, 33, 34, 35 is inserted in the delivery pipe 30, 31 leading from the pressure valves 8 to the consumer. The disc 32 of the

35 valve is loaded by a spring 33 arranged in the valve casing 34, so as to abut against the end wall thereof, and a piston 35 is arranged in the casing 34 and connected to the valve disc 32 in such manner that a discharge of compressed gas or air from the chambers 6 takes place only, when a predetermined pressure adapted for the operation of the engine is reached. To this end the casing 34 is connected on the side of the piston 35 opposite to the spring 33 by means of a connection 36 to a container 20 communicating with one of the storing chambers 9 through a small bore 37. 38 are exhaust pipes connected to the storing chambers 9, respectively, and provided with control valves 39.

40 The exhaust pipe 46 of the motor cylinder is connected to a suitably arranged exhaust port 41 by means of a connection 45. 40 is a valve disc loaded by a spring 42 arranged in a cylinder 44' and normally closing valve 40. The upper end of the valve stem is provided with a piston 44 arranged in the cylinder 44' and lifted by the spring 42. The upper part of the cylinder 44' is connected to the container 20 by means of a connection 43.

The operation of the engine is as follows:

45 Before the start all parts of the engine are in the positions shown in Fig. 1, the pistons 26 being set by means of the buttons 27' and the reciprocating bodies being brought into their outer dead centre positions by suitably rotating the pinion 15 by means of a crank handle (not shown) or the like. In this position the parts are secured by means of the locking device 17, 18. The exhaust valves 39 and the valves 32 and 40 are closed. When the inlet valves 22 are opened, compressed gas will flow into the storing chambers 9 and the container 20. In consequence thereof valves 32 and 41 will be opened, since the compressed air is fed to the cylinders 34 and 44'. Now the locking device 17, 18 is released by depressing the lever 19, so that the flying bodies are moved inwardly by the compressed air present in the storing chambers 9 and the air entering these chambers through the pipes 21, 23. During the inward stroke air is sucked into the chambers 6 through suction valves 7. During the last part of the stroke the pistons 3 move past the openings 25, so that compressed air enters the cylinders 26' and moves the pistons 26, whereby the piston rods 27 close the connections 23 and the flow of compressed air into the storing chambers 9 is interrupted. A portion of charging air will be discharged during the stroke from the motor cylinder 11 through the exhaust port 40, connection 45 and exhaust pipe 46. The charge in the motor cylinder 11, after having been compressed, is ignited whereby the flying bodies are driven outwards, compressing the air in the compressor cylinders 12, whereafter the cycle is repeated. During the first starting strokes the pressure in the container 20 is not materially affected owing to the small diameter of the bore 37. In consequence thereof valve 32 remains open and the compressors 2, 6 run idle during the starting strokes.

50 In order to gradually transfer the load from the starting device onto the compressors, the valves 39 are slowly opened. In consequence thereof the pressures in the storing chambers 9 and the container 20 are diminished, so that the valves 32 and 40 are gradually closed. By the closing of valve 32 the compressors are gradually loaded in correspondence to the unloading of the storing devices by the discharge of air

through valves 39, until the entire load is taken up by the compressors, the storing devices now running idle. By closing the valve 40, no charging air can escape from the motor cylinder 11, so that the engine now operates in the same manner as an ordinary free piston engine.

Referring now to Fig. 2, a container 50 is provided connecting the connection 38 to the discharge pipe 31. The container is dimensioned in such manner as to be charged to normal operating pressure within a predetermined number of strokes after the starting of the engine. Thus valve 32 will open after the normal pressure has been reached in the container 50. The inlet pipes 21 are directly connected to the storing chambers 9, displaceable bores 46, corresponding to bores 28 of the device shown in Fig. 1, being arranged in the outlet pipes 38 of the storing chambers 9, the outlet valves 39 shown in Fig. 1 being omitted in Fig. 2. The bores 46 are provided in piston rods 47 connected to auxiliary pistons 49 arranged in cylinders 49' which are connected to the container 50 by means of connections 51 respectively. The pistons 49 are loaded by means of springs 52 abutting against discs 52a and 52b arranged in casings 52c. The discs 52a are connected to the piston rods 47, while discs 52b are adjustable by means of adjusting screws 52d extending through the outer end walls of the casings 52c. Obviously the pistons 49 will be moved against the action of the springs 52, when the pressure in the container 50 increases. When no pressure exists in container 50, the pistons 49 are in a position in which the pipes 38 are closed by the piston rods 47. The pipes 38 are gradually opened, when the pressure in container 50 increases gradually.

Besides this a device is provided for automatically changing the fuel delivery to the motor cylinder 11 during the starting. To this end the piston 54 of the fuel delivery pump, the cylinder 54' of which is connected in the usual manner to the fuel delivering nozzle 16 of the cylinder 11, is driven from a rotating cam 55 by means of a double-armed lever 56 pivoted to the outer end of the piston 58 and sliding with one end on the cam 55. The other end of the lever 56 is connected to the rod 58' of a piston 58 arranged in a cylinder 58'' connected to the connection 30. 57 is a spring forcing the piston 58 to the left. When the pressure in the container 50 increases, the lever 56 is rotated in such manner that the piston 54 passes over an increasing portion of the inlet opening 59 of the cylinder 54', so that the amount of fuel delivered to the motor cylinder 11 increases with the increase of pressure in the container 50.

The operation of this device is substantially the same as that of the device shown in Fig. 1, except that the opening of valve 32 is controlled by the increasing pressure in the container 50 and that this pressure at the same time controls the opening of the pipes 38, so that the storage devices are gradually unloaded, while the compressors are loaded by the opening of the valve 32. Further in correspondence to the increase of pressure in the container 50 the output of the fuel delivery pump is increased.

I wish it to be understood that I do not desire to be limited to the exact details of construction shown and described, for obvious modifications will occur to a person skilled in the art.

I claim:

1. A free piston engine comprising in combination, a free piston including a motor piston ar-

ranged for operation in a motor cylinder, a compressor piston arranged for operation in a compressor cylinder, and an auxiliary piston arranged for operation in an auxiliary cylinder; a space in said auxiliary cylinder located on the side of the face of said auxiliary piston, means for connecting the auxiliary cylinder space with a source of gas under pressure and for shutting off said space from this source after it has been filled with gas under pressure; an outlet leading into the open provided on the auxiliary cylinder, a valve for shutting off and gradually opening said outlet; a pressure pipe associated with said compressor cylinder, a valve provided in said pressure pipe and adapted to afford passage to the pressure gas coming from the compressor once a predetermined compression end-pressure has been reached, means controlled in dependency upon the variable gas pressure in a space, which is connected with one of the two last named cylinders, these means being adapted to influence the valve of the other of the said cylinders in a manner such that the compressor reaches the pressure corresponding to normal operation when the auxiliary cylinder is completely emptied of pressure gas and is connected with the atmosphere.

2. A free piston engine comprising in combination, a free piston including a motor piston arranged for operation in a motor cylinder, a compressor piston arranged for operation in a compressor cylinder, and an auxiliary piston arranged for operation in an auxiliary cylinder; a space in said auxiliary cylinder located on the side of the face of said auxiliary piston, means for connecting the auxiliary cylinder space with a source of gas under pressure and for shutting off said space from this source after it has been filled with gas under pressure; an outlet leading into the open provided on the auxiliary cylinder, a valve for shutting off and gradually opening said outlet; a pressure pipe associated with said compressor cylinder, a valve provided in said pressure pipe and adapted to afford passage to the pressure gas coming from the compressor once a predetermined compression end pressure has been reached, means controlled in dependency upon the variable gas pressure in a space, which is connected with one of the two last named cylinders, these means being adapted to influence the valve of the other of the said cylinders in a manner such that the compressor reaches the pressure corresponding to normal operation when the auxiliary cylinder is completely emptied of pressure gas and is connected with the atmosphere; means for temporarily locking the free piston in substantially its outermost dead-center position with respect to the motor piston, and means for rendering said locking means inoperative.

3. A free piston engine according to claim 1, including a device for supplying fuel to the motor cylinder; a space connected with one of the other two cylinders and further connected with a pressure controlled device for varying the fuel supply in a manner such that the fuel supply, which is still low when the engine is started, increases to the amount corresponding to normal operation in proportion to the variation of the pressure prevailing in this space from the start to the attainment of normal operating conditions.

4. A free piston engine according to claim 1, including an exhaust port on the motor cylinder adapted to be covered by the motor piston only after this piston has travelled a certain distance

from its outermost dead center position, an adjustable closure member in said exhaust port; a space connected with one of the two other cylinders and further connected with a pressure controlled device for varying the position of the closure member in a manner such that this closure member, which is open when the engine is started, gradually throttles the exhaust port until it is completely shut in proportion to the variation of the pressure in the space from the start to the attainment of normal operating conditions.

5. A free piston engine comprising in combination, a free piston including a motor piston arranged for operation in a motor cylinder, a compressor piston arranged for operation in a compressor cylinder and an auxiliary piston arranged for operation in an auxiliary cylinder; a space in said auxiliary cylinder located on the side of the 10 face of said auxiliary piston, means for connecting the auxiliary cylinder space with a source of gas under pressure and for shutting off said space from this source after it has been filled with gas under pressure; an outlet leading into the 15 open provided on the auxiliary cylinder; a valve adapted for manually shutting off and gradually opening said outlet; a pressure pipe associated with said compressor cylinder, a reservoir constantly connected, through a narrow passage, 20 with the auxiliary cylinder space and further connected with a spring loaded valve provided in said pressure pipe in a manner such that the pressure prevailing in said reservoir opposes the action of the spring of said spring-loaded valve; 25 a shut-off device provided in the gas supply pipe leading to the auxiliary cylinder space, a piston connected with this device, a cylinder space surrounding this piston and connected, through a

channel, with the auxiliary cylinder space, said channel opening into the auxiliary cylinder space at a point which is laid open by the auxiliary piston when it has travelled, starting at its outermost dead center position, with respect to the 5 motor piston, over a greater portion of its stroke.

6. A free piston engine comprising in combination, a free piston including a motor piston arranged for operation in a motor cylinder, a compressor piston arranged for operation in a compressor cylinder, and an auxiliary piston arranged for operation in an auxiliary cylinder; a space in 10 said auxiliary cylinder located on the side of the 15 face of said auxiliary piston, means for connecting the auxiliary cylinder space with a source of gas under pressure and for shutting off said space from its source after it has been filled with gas under pressure; an outlet leading into the open provided on the auxiliary cylinder, a shut-off 20 valve permanently loaded for closing provided in this outlet, a pressure pipe associated with said compressor cylinder, a container in said pressure pipe, a valve loaded for closing provided in the outlet from said container adapted to afford passage 25 only when the pressure in said container has reached the amount of the normal compressor end pressure, said container being connected with a pressure controlled device for adjusting the shut-off valve in the outlet from the auxiliary cylinder in opposition to the spring arranged on said shut-off valve, in a manner such that this auxiliary cylinder outlet is completely open when the pressure in said container has reached the 30 normal compressor end pressure. 35

HERMANN JÄNICKE.
